CLAIM

The ornamental design for a curved needle with two ports, as shown and described.

DESCRIPTION

FIG. 1 is an isometric view of a curved needle with two ports showing my new design;

FIG. 2 is front elevation view thereof;

FIG. 3 is a rear elevation view thereof;

FIG. 4 is a left-hand elevation view thereof;

FIG. 5 is a right-hand elevation view thereof;

FIG. 6 is a top plan view thereof; and,

FIG. 7 is a bottom plan view thereof.

The broken lines in FIG. 3 represent an interior area of one port and do not form any part of the claimed design.

1 Claim, 7 Drawing Sheets(56)
